[57] CLAIM

The ornamental design for an adjustable garment
hanger, as shown and described.

DESCRIPTION

FIG. 1 is a perspective view of an adjustable garment
hanger showing my new design, in its opened form;
FIG. 2 is a perspective view thereof, in its closed form;
FIG. 3 is an enlarged right side elevational view
thereof;
FIG. 4 is an enlarged left side elevational view thereof;
FIG. 5 is an enlarged top plan view thereof;
FIG. 6 is an enlarged front elevational view thereof, the
rear being a mirror image;
FIG. 7 is an enlarged bottom plan view thereof;
FIG. 8 is a perspective view of a second embodiment of
the design of FIG. 1, in its opened form;
FIG. 9 is a perspective view of FIG. 8, in its closed
form;
FIG. 10 is an enlarged right side elevational view of
FIG. 8;
FIG. 11 is an enlarged left side elevational view of FIG.
8;
FIG. 12 is an enlarged top plan view of FIG. 8;
FIG. 13 is an enlarged front elevational view of FIG. 8,
the rear being a mirror image;
FIG. 14 is an enlarged bottom plan view of FIG. 8.
